CLAIM

The ornamental design for a washer toss game apparatus, as shown and described.

DESCRIPTION

FIG. 1 is a bottom plan view of my new design for a washer toss game apparatus;

FIG. 2 is a top plan view thereof;

FIG. 3 is a left side elevational view thereof, the opposite side being a mirror image thereof;

FIG. 4 is an end elevational view thereof, the opposite end being a mirror image thereof;

FIG. 5 is an enlarged elevational view of any one of the cavities shown in FIG. 1; and,

FIG. 6 is a cross sectional view taken on line 6-6 of FIG. 5, further disclosing the circular nature of the cavity wall.
